US00D878824S

(12) **United States Design Patent** (10) **Patent No.:** **US D878,824 S**
(45) **Date of Patent:** **** Mar. 24, 2020**

(54) **CLOTHES RACK**

(71) Applicant: **Immobiliare Metalprogetti SRL**,
Perugia (IT)

(72) Inventor: **Augusto Santicchi**, San Sisto (IT)

(73) Assignee: **Immobiliare Metalprogetti SRL**,
Perugia (IT)

(**) Term: **15 Years**

(21) Appl. No.: **29/662,377**

(22) Filed: **Sep. 5, 2018**

(30) **Foreign Application Priority Data**

Mar. 5, 2018 (EM) 4740124

(51) **LOC (12) Cl.** **20-02**

(52) **U.S. Cl.**

USPC **D6/672**
